DESIGN FOR A CREAM DISPENSER

Charles E. Swann, Glencoe, Ill., assignor to Craft Manufacturing Co., Chicago, Ill., a corporation of Illinois

Application December 23, 1940, Serial No. 97,568

Term of patent 14 years

To all whom it may concern:

Be it known that I, Charles E. Swann, a citizen of the United States, residing at Glencoe, Cook County, Illinois, have invented a new, original, and ornamental Design for a Cream Dispenser, of which the following is a specification, reference being had to the accompanying drawing, forming a part thereof.

I claim:

The ornamental design for a cream dispenser, substantially as shown.

CHARLES E. SWANN.
